US00D582479S

(12) United States Design Patent
Cetera

(10) Patent No.: US D582,479 S
(45) Date of Patent: * Dec. 9, 2008

(54) INK REFILL

(75) Inventor: Carl Cetera, Tenafly, NJ (US)

(73) Assignee: Cotapaxi Custom Design and Manufacturing, LLC, Carlstadt, NJ (US)

() Term: 14 Years

(21) Appl. No.: 29/253,606

(22) Filed: Feb. 8, 2006

(51) LOC (8) Cl. 19-06

(52) U.S. Cl. D19/55

(58) Field of Classification Search .... D19/35, D19/36, 41-51, 53-57; 24/11 F, 11 P, 11 R; 401/52, 99, 100, 104-109, 192, 195, 196, 401/132-134, 198, 217
